[57] **CLAIM**

The ornamental design for a universal surgical handle, as shown and described.

DESCRIPTION

FIG. 1 is a perspective view of a universal surgical handle. The broken line showing of the drill guide sleeve is for illustrative purposes only and forms no part of the claimed design;

FIG. 2 is a side elevational view thereof;

FIG. 3 is a front elevational view thereof;

FIG. 4 is a rear elevational view thereof;

FIG. 5 is a side elevational view thereof of the side opposite the side shown in FIG. 2;

FIG. 6 is a top plan view thereof; and,

FIG. 7 is a bottom plan view thereof.
